Primary Examiner — Philip S Hyder(74) *Attorney, Agent, or Firm* — C. G. Mersereau; Nikolai & Mersereau, P.A.(57) **CLAIM**

The ornamental design for a hammer, as shown and described.

DESCRIPTION

FIG. 1 is a perspective view of a hammer, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the hammer in which the design is embodied that are not considered part of the claimed design.
